United States Patent Office

Des. 186,818
Patented Dec. 8, 1959

186,818

BRACELET WATCH

Leo Gale, Hewlett, N.Y., assignor to Gruen Industries,
Inc., New York, N.Y., a corporation of Ohio

Application September 6, 1957, Serial No. 47,637

Term of patent 14 years

(Cl. D42—8)

Fig. 1.

Fig. 2.

Fig. 3.

Fig. 5.

Fig. 4.

Figure 1 is a perspective view of a bracelet watch showing my new design;

Figure 2 is a side elevational view thereof;

Figure 3 is a top plan view thereof;

Figure 4 is a bottom plan view thereof; and

Figure 5 is an end view thereof.

The dominant features of my design reside in the portion shown in full lines.

I claim:

The ornamental design for the bracelet watch, substantially as shown and described.
